UNITED STATES PATENT OFFICE

2,632,913

CONVERTER ARRANGEMENT FOR SUCTION
CLEANERS

Edward R. Swann, North Canton, Ohio, assignor
to The Hoover Company, North Canton, Ohio,
a corporation of Ohio

Application May 20, 1950, Serial No. 163,258

5 Claims. (Cl. 15—324)

1

This invention relates to suction cleaners and more particularly to a converter arrangement for converting the cleaner from on-the-floor cleaning to off-the-floor cleaning operation.

Specifically, according to the present invention the cleaner is provided with a top front converter opening in which the converter may be inserted downwardly and rearwardly into the suction passageway so as to substantially close off the suction passageway between the fan eye and nozzle. The closure for the converter opening also forms the cover plate for a headlight receiving housing and also the top furniture bumper. The closure forms a continuation of the appearance hood mounted on top of the main body of the cleaner.

Other objects and advantages of this invention will become apparent as the description proceeds when taken in connection with the accompanying drawings in which:

Figure 1 is a perspective view of a suction cleaner showing the present invention applied thereto;

Figure 2 is a sectional view through the converter opening showing the converter in place; and

Figure 3 is a perspective view of the inner end of the converter tool.

Referring to the drawings, the main body or chassis 10 is mounted for ambulatory movement on front and rear wheels 11 and 12 respectively and is formed with a downwardly facing nozzle 13 with a bumper 14 of rubber or other resilient material suitably secured about the sides and front thereof.

A casing 15, having a motor-fan unit therein, extends transversely of the body 10 and is pivoted thereto on a horizontal axis by trunnion bearings similar to the manner shown in the patent to Burkhardt 2,225,621 dated December 24, 1940. Rigid with the casing 15 is an exhaust nozzle 16 and a handle socket 17. The exhaust nozzle 16 detachably receives the open lower end of a filter bag 18 the upper end of which is supported from the handle 19.

The casing 15 and the body 10 are formed with a fan eye 20 opening through one of the trunnions into a suction passageway 21 formed in the body 10 and extending forwardly and downwardly to the suction nozzle 13. An agitator (not shown) of any suitable construction is rotatably mounted in the nozzle 13 in a position to contact the surface covering as it is drawn upwardly against the nozzle 13 by the suction created by the fan. A pulley 22 formed as an extension on the fan shaft extends through the

2

fan eye 20 into the suction passageway 21 and drives the belt 23 which in turn drives the agitator. The lower side of the suction passageway 21 is closed by a removable closure plate 24 to provide access to the belt and pulley.

An appearance hood 25 is mounted on top of the body 10 and extends from the rear thereof along the sides of the casing 15 and forwardly therefrom so as to form a housing above and to the rear of the nozzle 13. A headlight 26 is located in the housing centrally thereof and to one side thereof at the end above the suction passageway 21 is a converter receiving tube 27 which opens into the top of the suction passageway 21 and slopes downwardly and rearwardly as shown.

The tube 27 detachably receives the lower end of a converter tool 28 having its forward end cut away to form a rearwardly facing opening 29. The belt 23 lies close to the inner wall of the suction passageway 21 and the tool 28 is recessed at 30 to receive the belt. The lower end of the converter tool is of such shape and size as to close off the remainder of the suction passageway except for the recess 30 which receives the belt 23. A latch 31 carried by the tool 28 snaps into an opening 32 in the outside wall of the tube 27 to latch the tool in place. The latch may be released by pressing inwardly on its handle 33.

The converter receiving tube 27 and the housing which receives the headlight is closed by a combined converter opening closure, lamp housing door and furniture guard generally indicated by the reference numeral 35. The member 35 is pivoted to the body 10 at 36 and is adapted to be held either in its open or closed position by a flat spring 37. The member 35 is provided with louvers 38 in its front forwardly of the light 26 so that light rays may be projected forwardly onto the surface to be cleaned. A soft furniture guard 39 of rubber, thermoplastic or other suitable material is secured to the member 35 along its ends and top so that furniture, etc., will not be marred when the cleaner is pushed beneath it. On its inner side the member 35 is provided with an inwardly offset closure 40 which fits over the mouth of the converter receiving tube 27 when the member 35 is moved to its closed position and forms a sort of guide for guiding the converter tool 28 into the converter receiving opening 27 when the member 35 is in its open position.

From the foregoing it can be seen that this invention provides a simple construction whereby the converter tool can be easily inserted from the top front of the cleaner by a simple downwardly

rearward movement thereof and latched in position whereby the cleaner may be pulled about by pulling on a hose attached to the upper end of the converter tool.

While I have shown but a single embodiment of my invention it is to be understood that this embodiment is to be taken as illustrative only and not in a limiting sense. I do not wish to be limited to the particular structure shown and described but to include all equivalent variations thereof except as limited by the scope of the claims.

I claim:

1. A suction cleaner comprising, a body mounted for ambulatory movement, a motor-fan unit including a casing extending transversely across said body on a horizontal axis and having a fan eye at one end thereof, said body being formed with a downwardly facing suction nozzle and a suction passageway extending upwardly and rearwardly from said nozzle to said fan eye at one end of said body, a converter receiving tube communicating with said suction passageway through the top wall thereof adjacent one end of said body and sloping downwardly and rearwardly into said suction passageway, a light mounted on said body centrally thereof to one side of and in line with said converter receiving tube transversely of said body, a housing extending transversely across said body above said light and converter receiving tube and having a front opening, and a closure for said opening in front of said light and said converter receiving tube.

2. A suction cleaner according to claim 1 in

which said housing is formed by a horizontal forwardly opening streamlined appearance hood and said closure forms a continuation of said streamlined appearance hood.

5. A suction cleaner according to claim 2 in which said closure is pivoted to said body so as to lie on said body in front of said appearance hood when it is in its open position.

10 6. A suction cleaner according to claim 3 in which said closure is provided with an inward offset portion which lies against the mouth of said converter receiving tube when said closure is closed and forms a guide for guiding a converter tool into said converter receiving tube when 15 said closure is open.

7. A suction cleaner according to claim 3 including spring means for holding said closure both in its open and closed positions.
